ARTIST'S BOX

Irwin Brooks, Merrick, and Alan Friedberg, Lynbrook, N. Y., assignors to American Artists' Color Works, Inc., Brooklyn, N. Y., a corporation of New York

Application May 3, 1950, Serial No. 159,742

3 Claims. (Cl. 45—129)

1

When artists go out into the field to paint and sketch they generally take with them their boxes which contain their equipment including colors, brushes, and canvases. These boxes have generally involved a main body compartment and a cover. The covers heretofore have been provided with opposed side walls formed with oppositely disposed slots to receive and house the canvases. When the box is opened and the cover is in open upright position, the canvases can be lifted out of their respective slots and disposed against the cover in various manners to dispose them in position for sketching or painting. Heretofore the canvases were left housed in the slots of the cover and the artists painted thereon while they were thus housed. It is obvious that in this position the entire area of the canvas would not be available to the artist for the painting thereon. Various constructions have been hitherto provided to permit these canvases to be thus disposed, but most of them have involved expensive complicated structures which, because of cost and complexity, have thus been proved to be impractical.

An object of the present invention is to provide a simple, efficient, inexpensive construction which will permit the canvas to be disposed in operative position for painting or sketching, in such a position removed from the cover-housing slots so that the entire area of the canvas is readily available to the artist in a convenient position.

A further object is to provide a construction which involves a minimum of parts and no major alteration in the usual structure of the boxes now in use.

Further and more specific objects, features and advantages will more clearly appear from a consideration of the detailed specification hereinafter set forth, especially when taken in connection with the accompanying drawings which illustrate a present preferred form which the invention may assume and which form part of the specification.

In brief and general terms, the invention involves a cover which has a pair of side walls having opposed slots therein in which canvases are housed. The improvement comprises cutting one or more slots across these normal vertical slots and slightly inclined rearwardly and downwardly to receive a shelf element on the upper surface of which are formed a series of parallel slots. When the shelf is thus disposed in one or the other of the cross cut slots above mentioned with its slotted face disposed up-

2

wardly, the canvas which has been removed from the normal housing slots can be disposed with its lower edge disposed in one or the other of the slots in the upper face of the shelf and its upper edge inclined rearwardly and lying against the upright cover member. Thus the artist, by a simple arrangement of an extra shelf and the novel construction of the cross cut slots, may dispose his canvas as desired.

10 The present preferred form which the invention may assume is illustrated in the drawings, of which,

Fig. 1 is a perspective view of the device with the cover opened and showing a canvas disposed with respect thereto in operative position;

15 Fig. 2 is a vertical cross section taken on the line 2—2 of Fig. 1; and,

Fig. 3 is a detail showing a canvas disposed operatively in another position.

20 Referring now merely to the specific preferred form of the invention shown in the drawing, it is to be noted that the box, in general arrangement, is of the usual type, having a main body portion 10 and a pivoted cover 11 suitably related by hinge elements 12. The body portion may be provided with any suitable arrangement of compartments 13 to receive artist's material such as paints, brushes, and the like. The cover is provided with side walls 14 and 15 which on their adjacent faces are provided with a series of spaced slots 16 extending longitudinally thereon. These slots are provided to receive and hold one or more canvases A on which the artist may desire to sketch or paint.

25 In order to permit the artist to use the box as a support for his canvas in a desired convenient position for sketching or painting, we have provided the adjacent faces of the side walls with cross cut slots 17 and 18 at different levels, and cut with a slight rearward and downward slope as shown. These transverse, or cross cut slots, are provided to receive one edge portion of a supporting shelf 19 which is slipped into one or the other of said slots. This shelf on its upper surface is provided with a series of longitudinal parallel spaced grooves 20. With this shelf disposed in one or the other of said slots, which will be seen from the drawings, the canvas A on which it is desired to sketch or paint may be pulled out of the slots 16 in the cover and disposed with its lower edge in one of the slots 20 on the shelf 19, and sloping upwardly and rearwardly to rest against the cover. If the canvas is disposed with its longer edge resting in the grooves 20, its upper portion will

30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

rest against the front of the side walls 14 and 15 as shown in Fig. 3, but if its shorter edge rests in the groove 20 then its upper portion will lie between the side walls and against the back edge of the cover.

It will thus be observed that by taking the usual artist's box and providing the canvas-receiving slots with transversely cut slots to receive a supporting shelf we have enabled the artist by the use of only one additional element, namely, the shelf 19, and without any major alteration of the box, to securely dispose his canvas on the box at any one of several desired angles for the purpose of facilitating his work without having to have a separate easel or similar support. When the artist is through with his sketching, he removes the canvas from the support 19, houses it in one of the slots 16, places the shelf in the top of the main body portion, and then closes the cover, thus making a very simple, efficient and useful construction.

While the invention has been described in detail and shown with respect to the accompanying drawing, it is not to be limited to such details, since many changes and modifications may be made in the invention without departing from the spirit and scope thereof. Hence, it is desired to cover any and all forms and modifications of the invention which may come within the language and scope of any one or more of the appended claims.

We claim:

1. An artist's box including a cover portion having side walls, the inner faces of which are provided with a series of transverse slots adapted to receive a canvas supporting shelf having a series of longitudinal slots in its upper surface, said transverse slots inclining slightly downwardly and rearwardly when the cover portion is in the fully opened position, whereby a canvas may adjustably lean against the cover with its lower edge

resting in one of the longitudinal slots of said shelf.

2. In an artist's box which includes a cover having side walls, a canvas supporting shelf having longitudinal parallel slots in its upper face, pairs of parallel transversely cut slots in the inner faces of said side walls, said shelf adapted to be received in a pair of slots in a direction generally transverse to the length of said side walls, said transversely cut slots sloping generally rearwardly and downwardly when said cover is in open position, any one of said longitudinal slots on said shelf being adapted to receive the lower edge of a canvas.

3. In an artist's box which includes a cover having side walls, a canvas supporting shelf having longitudinal parallel slots in its upper face, a plurality of pairs of transversely cut slots in the inner faces of said side walls, each pair adapted to receive and retain said shelf on the cover in the direction generally transverse to the length of said side walls, said transversely cut slots in the side walls sloping slightly rearwardly and downwardly when said cover is in open position, each one of said longitudinal slots on said shelf adapted to receive the lower edge of a canvas so that the canvas can be positioned on said shelf in a plurality of positions.

IRWIN BROOKS.
ALAN FRIEDBERG.
